UNITED STATES PATENT OFFICE

HERBERT S. HART AND LLOYD J. WHITE, OF SAN ANTONIO, TEXAS, ASSIGNEES TO
SOUTHERN PRISON COMPANY, OF SAN ANTONIO, TEXAS, A CORPORATION OF TEXAS

ACTUATING MECHANISM FOR CELL DOORS AND LOCKS

Application filed July 6, 1931. Serial No. 549,042.

This invention relates to master actuating mechanism for a plurality of cell doors and locks and, among other objects, aims to provide important improvements in systems of the general type disclosed in the co-pending application of White and Youngblood, Serial No. 451,142, filed May 9, 1930. The main idea is to provide a relatively simple system of gearing and associated means for imparting actuating movement, first, to the selected doors and second, to the selected doors without reversing the gearing so that motive or manual power may be applied continuously without interruption to unlock, open and lock open any selected door or doors and power may be applied through the same mechanism to unlock, close and relock the opened doors. When such systems are operated manually by means of a lever or hand wheel, it is very desirable to reduce the number of operations to a minimum so that the jailer or operator will not have to depend too much upon his memory of a series of steps. Moreover, he should be able to select and actuate any or all of the doors in a cell block very quickly in case of fire or of other hazardous conditions.

Other aims and advantages of the invention will appear in the specification, when considered in connection with the accompanying drawings, wherein:

Fig. 1 is a fragmentary vertical sectional view showing one embodiment of the operating mechanism applied to systems having master bars for actuating a series of doors and locks;

Fig. 2 is a fragmentary sectional view taken on the line 2-2 in Fig. 1;

Figs. 3 and 4 are sectional views taken on the lines 3-3 and 4-4, respectively, in Fig. 1; and

Figs. 5 to 8 inclusive, are detail views each showing adjacent parts separated to explain the sequence of operations and the relative positions of the parts.

Referring particularly to the drawings, the preferred form of actuating mechanism is there shown as being employed in a master lock and door operating system employing the usual master bars which are adapted to be selectively connected to the respective

locks and doors by mechanism such as those disclosed in the patents to D. F. Youngblood, Nos. 1,269,244, 1,611,260 and 1,785,471. Since the present invention relates solely to operating means for imparting lock and door actuating movements in proper sequence to the master bars, illustration of a complete system is unnecessary. It is known in the art that one may use selector levers or buttons in a master control box to effect the selective connections between master bars or operating members and the locks and doors.

In Figs. 1 to 4 inclusive, the mechanism is shown as being mounted in the usual housing 10 above the cells and is arranged to actuate a door propelling bar 11 and lock operating bar 12, both guided to reciprocate longitudinally in the housing. It is here shown as being connected to the bars intermediate their ends so that it may be located in the housing between two adjacent cells. Actuating movement is adapted to be imparted to the mechanism by a single lever or hand wheel 13 arranged in a master control box 14 at the end of the row of cells. 75

In this example, the mechanism comprises a system of intermittent gearing so constructed and arranged as to impart successive lock and door actuating movements to the bars 11 and 12 upon turning the hand wheel in one direction. The idea is to impart unlocking movement to the master lock operating bar; then, door opening movement to the master door propelling bar while the other bar is inactive; and, then, locking movement to the lock operating bar to relock the doors in open position, by simply turning the wheel continuously in one direction. The above sequence of operation is reversed to unlock, close and relock the selected doors by turning the hand wheel continuously in the reverse direction. The object is to so simplify the operation as to enable any prison keeper to work the mechanism without having to memorize a more or less complicated series of steps. The intermittent gearing is therefore constructed to impart the successive sequential movements to the bars. 95

For the sake of simplicity, it will be assumed that the two master bars are common 100

to all of the doors in a single row of cells and that only one set of intermittent gears is employed to operate the bars. In this example, the gearing is mounted on a bracket 15 secured to the bottom of the housing 10. A transverse, non-circular shaft 16 is journaled in the bracket and is adapted to be driven by a bevel gear 17 splined thereon and meshing with a bevel gear 18 on a jointed shaft 19. The hand wheel is shown as being connected to drive the jointed shaft by bevel gears 20 and a vertical shaft 21, Fig. 1. The main shaft 19 is connected to impart movement to both bars 11 and 12. The operating connection between the shaft 16 and master lock operating bar 12 includes an intermittent gear 22 splined on the shaft adjacent to the bevel gear 17 and meshing with an intermittent pinion 23 on a countershaft 24 journaled in the bracket 15. The countershaft carries an eccentric 25 outside of the bracket connected to a link 26 which is pivoted to the bar 12. The intermittent gear 22 has a sufficient number of teeth to rotate the small pinion through 180° in either direction and has a smooth portion 27 which engages a smooth part 28 on the pinion, thus locking the pinion while the gear is free to turn through approximately three quarters of a revolution. The tips of the teeth adjacent to the smooth part 28 on pinion 23 are so shaped as to accommodate the smooth part 27 and to mesh properly with the teeth on gear 22. The relative position of the gear and pinion when the doors are closed and locked is shown in Fig. 5, the bar 12 there shown as being at the right end of its travel. Upon rotating gear 22, counterclockwise to the position shown in Fig. 6, full unlocking movement (to the left) is imparted to the bar. Incidentally, Fig. 2 shows the bar 12 in its unlocking position.

After the selected doors have been unlocked, door opening movement must be imparted to the propelling bar 11 while the bar 12 is held inactive. In this example, the gearing is connected to impart such movement to the bar 11, while the smooth part 28 on gear 22 is riding on the smooth part 28 on pinion 23 and during about three quarters of a turn of shaft 16. Referring to Figs. 2, 3 and 4, the bar 11 is shown as being actuated by two similar intermittent gears 29 on the shaft 16 which straddles a rack bar section 30 shown as being removably secured to the bar 11 intermediate its ends. The upper edge of the rack section is smooth and bears against a spacer washer 31 between the gears while the teeth are on the lower edge. The gears 29 mesh with parallel, spaced racks 32 having roller bearings 33 which ride in a channel 34 in the bottom or base of the bracket 15. A fixed rack 35 secured in the bottom of the channel 34 and

pinion 36 mounted on a shaft extending through the middle of movable racks 32 meshes with the fixed rack 35 and the teeth on rack section 30. The arrangement is such that twice as much movement is imparted to rack section 30 or bar 11 as the movement imparted to the movable racks 32. This enables the mechanism to be made very compact so that it will not interfere with other mechanism in the housing 10. Further, the double gears and racks are not subjected to any lateral thrust or twisting strains.

The double, intermittent gears 29 have smooth peripheral portions 37 which engage concave recesses 38 in the opposite ends of movable, rack 32 (Figs. 5 to 8). The concave ends of the racks serve to limit the movement of the racks and the bar 11 and the relation of the smooth parts 37 on the gears 29 with respect to teeth on the toothed portion of the lock operating gear 22 is such as to hold the propelling bar 11 inactive while the gear 22 is rotating the locking pinion 23. In Fig. 1, the bar 11 has been moved to the extreme right end of its travel to open all selected doors. In Fig. 5, the parts are in door locking and closing position. The smooth parts 37 of gears 29 will turn in the right hand concavities 38 on the movable racks 32 while unlocking movement is being imparted to the bar 12 by gear 22 and pinion 23 or during approximately a quarter turn of shaft 16. In Fig. 6, the toothed portions of gears 29 are ready to engage the teeth on the movable racks 32 and drive the racks to the right until the smooth parts 37 engage the left hand concavities 38 in the racks. While this is being done the smooth part 27 of gear 22 is riding on the smooth part 28 of pinion 23, all selected doors having been unlocked.

Fig. 7 shows the position of the parts when the master propelling bar 11 has been moved to open all selected doors. Fig. 8 shows the parts after locking movement is imparted to bar 12 to lock the selected doors in open position. All of this is accomplished by continuously turning the operating shaft through one revolution. The hand wheel is preferably geared to turn only one round to do this. After the doors are opened and locked open, the hand wheel is adapted to be turned continuously in the reverse direction to unlock, close and relock the doors. The parts will then assume the successive positions shown in Figs. 7, 6 and 5 respectively. The gearing positively limits the movement of the hand wheel in either direction so that none of the parts can be jammed. Moreover, the operator has only to try the hand wheel and turn it in the right direction without remembering any instructions, since the wheel cannot be turned in the wrong direction.

From the foregoing description, it will be

seen that the improved system of gearing is relatively simple and easy to install. In fact, the main part of the mechanism can easily be assembled as a unit, so that it is ready to install. There are no complex or delicate parts which are likely to fail or cause trouble. The operation of the system is so simplified as to require only ordinary intelligence on the part of a jailer or operator. Further, it enables a jailer to release all prisoners very quickly in case of fire. The old double-lever systems require considerably more time and skill to operate.

Obviously, the present invention is not restricted to the particular embodiment thereof herein shown and described. Moreover, it is not indispensable that all the features of the invention be used conjointly, since they may be employed advantageously in various combinations and sub-combinations.

What we claim is:

1. In a jail cell installation having separate bars to actuate the doors and locks, actuating mechanism for the bars including intermittent gearing connected to the bars; means associated with the gearing connected to impart sequential movements to the bars as the gearing is rotated in either direction; and means for driving said gearing to effect said sequential movements.

2. In a jail cell installation having a locking bar and a door propelling bar, means to impart actuating movements in proper sequence to said bars, comprising a system of gears; and single driving means connected to the gearing and arranged to be moved continuously in one direction to impart said movements to the bars.

3. In a master lock operating and door propelling system for a series of cell doors wherein a master lock operating bar and a master door propelling bar are arranged in a housing, a system of gearing within the housing including means to impart actuating movements to the bars in proper sequence; and a single manually operable device connected to said gearing so as to impart continuous movement thereto in one direction.

4. In a jail cell installation having a locking bar and a door propelling bar, intermittent gearing arranged to impart movement to the door propelling bar; associated, intermittent actuating means connected to impart movement to the locking bar in proper sequence with respect to the door propelling bar; and power delivering means connected to said mechanism.

5. In a master lock operating and door propelling system for a series of cell doors wherein a master lock operating bar and a master door propelling bar are arranged within a housing above the doors, actuating mechanism for imparting successive movements to the bars including a system of intermittent gearing adapted to be rotated continuously in

one direction to impart said movements to the bars; and means associated with the gearing to lock each bar with respect thereto when the bar is inactive.

6. In a jail cell installation having a master lock operating bar and a master door propelling bar arranged in a housing over the cell doors, a bearing bracket mounted in the housing; a transverse shaft journaled in the bearing bracket; an intermittent gear on said shaft; an intermittent pinion meshing with said gear; a countershaft carrying said pinion; means on said countershaft connected to impart door locking and unlocking movement to the lock operating bar; associated gearing connected to impart intermittent actuating movement to the door propelling bar while the lock operating bar is inactive; interlocking means on said gearing positively preventing movement of either bar while the other is being actuated; and remote control means for driving the gearing.

7. In a jail cell installation having a master lock operating bar and a master door propelling bar arranged in a housing over the cell doors, a bearing bracket mounted in the housing; a transverse shaft journaled in the bearing bracket; an intermittent gear on said shaft; an intermittent pinion meshing with said gear; a countershaft carrying said pinion; means on said countershaft connected to impart door locking and unlocking movement to the lock operating bar; a pair of intermittent gears on said transverse shaft; a rack on the door propelling bar guided between said gears below the shaft and having teeth on its lower edge; a pair of parallel, movable racks meshing with said pair of intermittent gears and guided to reciprocate below the rack on the bar; a fixed rack mounted below said parallel racks; a pinion carried by said movable racks meshing with the fixed rack and the rack on the propelling bar arranged to impart twice as much movement to the bar as is imparted to the movable rack; 100 concave recesses at both ends of the movable rack to receive and interlock with said pair of intermittent gears and permitting the locking bar gearing to function while the propelling bar is inactive; and remote means connected to operate the gearing.

8. In a jail cell installation having a lock operating and a door propelling bar, a bearing bracket between the bars; a transverse shaft journaled in the bracket; means on the shaft connected to impart intermittent movement to the lock operating bar when the shaft is rotated continuously in either direction; intermittent gearing, including a series of racks connected to impart intermittent movement to the door propelling bar in sequence with respect to the movements of the lock operating bar; means automatically to lock either bar inactive while the other bar is be-

ing actuated; and remote control means connected to drive said transverse shaft.

9. In a jail cell installation having a lock operating and a door propelling bar, a bearing bracket between the bars; a transverse shaft journalled in the bracket; means on the shaft connected to impart intermittent movement to the lock operating bar when the shaft is rotated continuously in either direction; intermittent gearing, including a series of racks connected to impart intermittent movement to the door propelling bar in sequence with respect to the movements of the lock operating bar; means automatically to lock either bar inactive while the other bar is being actuated; and a single hand wheel connected to drive said transverse shaft.

10. In a jail cell installation having a lock operating bar and a parallel door propelling bar, actuating mechanism for imparting sequential movements to said bars including a transverse shaft carrying intermittent gears; remote control means connected to rotate the shaft; an intermittent pinion meshing with one of said intermittent gears connected to impart two lock operating movements to said lock operating bar upon continuous rotation of the said shaft in one direction; movement multiplying mechanism driven by the other intermittent gears connected to impart door operating movement to the door propelling bar while the lock operating bar is inactive; and interlocking means associated with said actuating mechanism to prevent either bar from being moved while actuating movement is being imparted to the other bar.

11. In a jail cell installation having a lock operating bar and a parallel door propelling bar, actuating mechanism for imparting sequential movements to said bars including a transverse shaft carrying intermittent gears; remote control means connected to rotate the shaft; an intermittent pinion meshing with one of said intermittent gears connected to impart two lock operating movements to said lock operating bar upon continuous rotation of the said shaft in one direction; a rack section secured to the door propelling bar adjacent to the other intermittent gears; a slidably mounted rack section connected to be driven by said intermittent gears when the lock operating mechanism is inactive; a fixed rack adjacent to the slidable rack and parallel with the rack section on the door propelling bar; a pinion meshing with the fixed rack and said rack section on the propelling bar; a shaft for said pinion secured to said slidable pinion whereby the pinion moves longitudinally with said slidable pinion and is simultaneously rotated on the fixed rack to impart greater movement to the propelling bar than that imparted to the slidable rack; and means on said slidable rack to limit the movement of said propelling bar in either direction.

12. In a jail cell installation having a master lock operating bar and a master door propelling bar, a system of intermittent gearing mounted adjacent to said bars; means connecting the intermitting gearing to impart actuating movement to said bars in sequence as the gears are rotated continuously in one direction; a jointed shaft connected to drive said gearing; and a single power delivering device connected to actuate said shaft.

In testimony that we claim the foregoing as our own, we have hereto affixed our signatures.
